CLAIM

The ornamental design for a card, as shown and described.

DESCRIPTION

FIG. 1 is a front elevation view of a first embodiment of the card, showing the new design;

FIG. 2 is a rear elevation view thereof;

FIG. 3 is a left side view thereof;

FIG. 4 is a right side view thereof;

FIG. 5 is a top plan of a view thereof; and

FIG. 6 is a bottom plan of a view thereof;

FIG. 7 is a front elevation view of a second embodiment of the card, showing the new design, with the top plan, left side, right side, and bottom plan views being the same as those is shown in FIGS. 3-6;

FIG. 8 is a rear elevation view thereof;

FIG. 9 is a front elevation view of a third embodiment of the card, showing the new design, with the top plan, left side, right side, and bottom plan views being the same as those is shown in FIGS. 3-6; and,

FIG. 10 is a rear elevation view thereof.

The broken lines shown in the drawings illustrate portions of the card that form no part of the claimed design.

1 Claim, 8 Drawing Sheets
